UNITED STATES PATENT OFFICE.

FRANKLIN H. TURNER, OF SATTLEY, CALIFORNIA.

COMBINED SAW CLAMP AND SET.

No. 863,562.

Specification of Letters Patent.

Patented Aug. 18, 1907.

Substitute for abandoned application, Serial No. 190,884, filed January 27, 1904. This application filed June 16, 1906.
Serial No. 322,053.

To all whom it may concern:

Be it known that I, FRANKLIN H. TURNER, a citizen of the United States, residing at Sattley, in the county of Sierra and State of California, have invented new and 5 useful Improvements in Combined Saw Clamps and Sets, of which the following is a specification.

This invention relates to a combined saw clamp and set, and the purpose of the same is to provide a device of this class which can be quickly set up for use in wood- 10 land tracts where a cross-cut or analogous saw is used for felling trees and capable of being supported on a stump or other object and operative to hold a saw-blade during a sharpening operation.

The invention consists in the construction and arrangement of the several parts which will be more fully hereinafter described and claimed.

In the drawing, Figure 1 is a perspective view of a saw-clamp, embodying the features of the invention, and shown applied in operative position and as holding 20 a saw-blade. Fig. 2 is a top plan of the clamp, and Fig. 3 is an end elevation of the clamp.

Similar numerals of reference are employed to indicate corresponding parts in the views.

The numeral 1 designates a supporting strip or bed, 25 having pairs of openings 2 arranged therein near opposite extremities, and flanges 2^a arranged adjacent its side edges to adapt it for holding tools. The bed, at opposite sides, has securing chains or analogous devices 3 attached thereto and provided with terminal hooks 4, 30 for securing in a stump or other object on which the supporting strip or bed 1 is disposed. Movablely extending through the openings 2 are uprights 5, having clamping jaws 6 secured to their upper extremities and movable transversely over the supporting strip or bed 1. 35 Extending transversely inward through one side edge of the supporting strip or bed 1, are clamping screws 7, to engage one set of uprights 5 and regulate the adjustment of the latter, and the jaw 6 carried thereby, in relation to the remaining jaw and uprights to accommodate 40 date variations in the thickness of saws. Movablely attached to the lower ends of the uprights 5, with which the screws 7 engage, are clamping levers 8, one on each upright, the said levers having inner enlarged or cam heads 9, to engage the inner edges of the uprights opposite those to which said levers are attached. The uprights with which the cam heads 9 of the levers 8 engage are disposed at one side of the uprights carrying said levers, as shown by Fig. 1, and by causing the said lever heads to engage the uprights, as explained, the one jaw 45 connected to the lever carrying uprights is firmly clamped against the saw-blade that may be disposed

between the jaws. This operation of clamping the jaws is rendered practical by the use of the set screws 7 which provide means for obstructing the outward movement of the uprights carrying the levers. In operating the 55 levers 8 to set up the clamping action of the jaws just explained, said levers are pulled upwardly, and in releasing the saw-blade, a reverse movement is given to said levers.

To adapt the clamp for holding narrow saw-blades 60 and projecting the teeth of the latter above the upper edges of the jaws, openings 10 are formed in the said jaws at suitable elevations to removably receive pins 11. The upper edges of the jaws 6 are curved to conform to the longitudinal curvature of the teeth of a saw-blade in order that the latter may be equally exposed 65 throughout the length of the blade held between the said jaws.

To support a saw-blade in horizontal position to permit its teeth to be set, arms 12 are pivotally mounted 70 upon the supporting strip or bed near its opposite extremities; said arms being adapted to be swung inwardly when not in use, as disclosed in Fig. 2 of the drawings, and outwardly to project their free ends beyond one side edge of the supporting strip or bed when 75 desired for use, as disclosed in Fig. 1 of the drawings. A saw set 13 is pivotally mounted upon the supporting strip or bed at a point centrally between the arms and is also adapted to be swung inwardly when not in use and outwardly to position its free end beyond the side 80 edge of the supporting strip or bed when desired for use. The under surfaces of the outer portions of the arms and saw set are removed, as at 14, to permit their free ends to be swung over the flange 2^a when moving the arms and saw set into position for use. The saw set is provided 85 with a downwardly and inwardly inclined working face 15 and with an adjustable gage 16. The upper surfaces of the inner portions of the arms are removed, as at 17, to permit a saw-blade to be moved thereon when setting its teeth without injury to the teeth. 90

The improved device will be found exceptionally useful, particularly in forests or woodland tracts where it is not always convenient to have a bench or other supporting means for a clamp. It will be understood that changes in the proportions, dimensions, and minor 95 details may be resorted to without in the least departing from the spirit of the invention.

Having fully described and illustrated the invention, what I claim is:

1. A saw clamp comprising a bed, means for securing 100 the bed to a stump or other support, said bed provided

2
with slots, one near each end thereof, upright clamping jaws extending through the slots, a set screw for adjusting one jaw member bodily toward the other to provide an adjustable fulcrum therefor, a cam lever for closing the jaws, and pivoted saw supporting and saw setting devices supported on the bed, substantially as described.

2. A saw clamp comprising a bed formed with transverse slots, clamping jaws resting upon and movable transversely of the bed, uprights secured to the jaws and pro-

jecting through the slots, and means for spreading the lower ends of the uprights to clamp the jaws.

In testimony whereof, I affix my signature in presence of two witnesses.

FRANKLIN H. TURNER.
